UNITED STATES PATENT OFFICE.

CHARLES R. EWING, OF BALTIMORE, MARYLAND, ASSIGNOR TO STANDARD OIL COMPANY, OF BAYONNE, NEW JERSEY, A CORPORATION OF NEW JERSEY.

APPARATUS FOR DISTILLING PETROLEUM.

1,083,998.

Specification of Letters Patent.

Patented Jan. 13, 1914.

Application filed November 25, 1911. Serial No. 662,406.

To all whom it may concern:

Be it known that I, CHARLES R. EWING, a citizen of the United States, residing at Baltimore city, in the State of Maryland, have 5 invented certain new and useful Improvements in Apparatus for Distilling Petroleum, of which the following is a specification.

This invention relates more particularly 10 to apparatus for distilling petroleum, but part of it at least can be used (with advantage, it is believed, over the prior state of the art) in apparatus for distilling other liquids; and possibly in relations other than 15 the distillation of liquids, as, for example, in bringing liquids and gases into contact with each other without distillation.

Each of the improvements composing the 20 invention is intended to be secured for all the uses to which it can be applied, with or without modification.

In distilling petroleum (as well as other liquids) use has heretofore been made of a vapor condensing tower so constructed that 25 descending condensate can be conveyed away separately or can be allowed to pass on in the tower, a flat bottomed stationary intercepting chamber with one or more overflows for allowing the condensate to pass on 30 after filling the chamber being provided and also a valved pipe for withdrawing the condensate from the chamber. A quantity of condensate corresponding with the horizontal area and depth of the chamber to the 35 overflow level is thus detained in the chamber when said pipe is closed; with the result that the condensate which passes on is of somewhat different composition from that which is received from above. Further, 40 when said stationary chamber is placed below a system of tubes or of other devices arranged for distributing the condensate over the horizontal area of the tower, it unites the condensate dripping from all the tubes 45 or other devices and so destroys the previous distribution of it. Again the flat bottom of the chamber exposes a surface to the vapors which is limited in area by the cross section of the tower and is of a character to have 50 little effect in commingling the vapors and the condensate.

In accordance with the present invention, the tower is provided with an interceptor which is movable and is so disposed that in

one position it conducts the descending condensate to the pipe for withdrawing the same and in another position allows the condensate to pass on (it may be and best would be) with little or no detention. When such movable interceptor is employed below a 55 system of condensing tubes or of other devices arranged for distribution of the descending condensate, as aforesaid, it can be, and best would be, adapted (in the appropriate position of the interceptor) to allow 60 the condensate to pass on with little or no interference with its distribution.

The interceptor is best composed of a number of movable slats or shutters, which in one position allow the descending condensate to 65 fall between them and in another position conduct such condensate to a pipe for withdrawing the same. Such slats or shutters, when open, may, and naturally would, form a grating which brings about a more intimate mingling of the condensate and the vapors; and they can be, and best would be, so arranged that, when closed, they constitute an inclined partition or partitions. Such partition or partitions act as a condensing means for the vapors; and, owing to 70 their inclined position, the surface area of them may (and, indeed, would naturally) exceed the cross section of the tower. It is further to be observed that stationary slats 75 or shutters may form a grating; that an inclined partition may be constituted otherwise than from slats or shutters, and that an interceptor within the limits of the invention may consist of slats or shutters which 80 are stationary or of an inclined partition or partitions in general, irrespective of the use. 85 of slats or shutters to compose the same.

While the interceptor is primarily intended to be placed between a higher and lower 90 part of a tower, it could within the limits of the invention be placed at the bottom of a tower.

Heretofore towers have been combined with heating means for forming vapors to 100 be treated (partially condensed, for example) in said towers under arrangements in which the liquids to yield said vapors are supplied to evaporators or stills without passing through the towers, and also under 105 arrangements in which such liquids are supplied to the towers themselves. The towers of the present invention are more particu-

larly intended to be used in arrangements of the former kind; but their use otherwise is not necessarily excluded.

In the accompanying drawings: Figure 1 is a plan view of a portion of distilling apparatus in accordance with the invention; Fig. 2 is a view of the same partly in elevation and partly in section; Figs. 3 and 4 are partial views in central vertical section of a tower in accordance with the invention, the sections being in planes at right angles to each other; and Fig. 5 is a partial view of said tower in plan.

The tower shown consists, first, of chamber *a* provided with a heat retaining jacket *b* thereon and baffles *c* in the form of cobble stones therein; and, second, of a system of tubes *d* inclosed in a casing *e* which has air inlets *f* and doors *g* therefor at the bottom and is open at the top. The tubes *d* connect at top with the annular header *h*, and are set at the bottom in the tube sheet *j*, constituting the top of chamber *a*. The flow of air over the tubes *d* and out through the header *h* carries off the heat from the vapors which pass through the tubes, the flow of air being regulated by opening and closing the doors *g* more or less; and if the doors *g* should be closed so completely as to prevent the flow of air, heat could be conducted away through the casing *e*; if this should be metal; as is preferred. The ends of the tubes *d* are so distributed that condensate falling from them, if not intercepted, would fall at different places over the top of the system of baffles *c*. When cobble stones are used as the baffles, they would best be from about four to eight inches in diameter. They rest on the grate *k*.

At *l* is a manhole.

As shown, the fire heated well jacketed still *m* has a vapor pipe *n* which leads to the tower *ad*; and a liquid pipe *p* branching from the pipe *s* leads from the tower to the still *m*. In pipe *p* is a valve *q*.

At *r* is the charging line for supplying petroleum to the still.

At *s* is a valve for letting on and shutting off the supply.

At *t* is a readily removable closure for the end of the T coupling *u*, forming part of the pipe *r*, such closure comprising a yoke and clamping screw and being used to enable pipe *r* to be cleaned.

At *w* is a valve pipe for service in steaming out the still at the end of each run.

At *x* is one of a number of columns used to support the still by means of lugs *x'* on the latter.

At *y* is a manhole.

The run back *p* is one of a plurality of pipes branching from the pipe *s* and leading from the tower *ad*. The pipe *2* serves for drawing off condensate through the

cooling water in tank *3*, when valve *4* in pipe *z* is open. The pipe *5* indicated with its valve *6* in dotted lines can be used for the same purpose (if desired) when the valve *4* is closed. The pipe *7*, with its valve *8*, is for drawing off condensate without conducting it through the water in tank *3*. It is used when the condensate will not flow at the temperature of the water. Cooling water is supplied by pipe *9* to tank *3*. Water overflows therefrom by pipe *10*. At *11* is an air cooled tubular condenser, connected at the bottom by vapor pipe *12* with the header *h* of tower *ad*.

At *13* is the beginning of a water cooled condenser (consisting of a pipe immersed in the water of tank *3* and) connected by vapor pipe *14* with the top of condenser *11*. From the bottom of condenser *11* a draw off pipe *15* conducts the condensate through the water of tank *3* for cooling when the valve *16* is open and the valve *17* in pipe *18* is closed; This pipe *18* interconnects the pipes *15* and *p* and enables the condensate from condenser *11* to be run back into the still *m*, when desired.

The liquid interceptor in tower *ad* is constituted as shown by a number of movable slats or shutters *20* (Figs. 3, 4 and 5) which in the position shown conduct descending condensate by way of the gutter *21* to the pipe *22* having a valve *23* and serving to convey condensate (it may be to any desired place, but as shown) to the draw off *2*, already referred to.

As shown, trunnions *24* on each slat or shutter *20* rest in notches in the frames *25*. Each frame *25* has at top a lug *26*, which passes through the wall of chamber *a* and is secured by an angle piece *27* to the metal cover of jacket *b*; and at bottom its lug *28* is secured to the gutter *21*, which passes through the walls of chamber *a* and is secured by flanges to the metal cover of jacket *b*. The upright flanged plate *29* closes the gutter *21* at that end. The frames *25* are set away from the walls of chamber *a*; so as to allow vapors to pass up around the frames.

The shutters, when closed, lap at their edges (see Fig. 4), the lower portion of each higher fitting over the upper edge of each lower shutter; and on what is in closed position the under side of each shutter near its lower edge there is a continuous bead or projection *30* for preventing condensate which may form on the under side of the shutter from flowing onto the shutter next below it. When the condensate reaches such a bead it drips off. The flanges *31* on the frames *25* cover the upper edges of the uppermost shutters in their closed positions. On each shutter at each end of it is a ridge or bead *32* to keep liquid from running over the shutter end.

To change the position of the interceptor the shutters are revolved on their trunnions, best until they stand vertical, the right hand section (as seen in Fig. 4) being moved 5 clockwise and the left hand section being moved counter clockwise. The rods 33 are each of them jointed to arms 34 on the shutters of its section; and the two lowermost shutters are interconnected by a rod 35 jointed to arms 36 fast on trunnions of said shutters. A shaft 37 provided with an operating handle 38 and passing through a stuffing box 39 is coupled to a trunnion of one of these shutters.

15 Vapors enter the tower by the pipe *n*, pass through the baffles *c* and then through the tubes *d*. Condensate formed in these tubes in the position shown of the movable interceptor 20 is conducted by way of the 20 gutter 21 to the pipe 22; which conveys it to the desired place (to draw off 2 as shown). Condensate would also collect on the under surfaces of slats or shutters 20 and would drop off onto the baffles *c*. By turning the 25 handle 38 until the shutters 20 are vertical, the condensate from tubes *d* can pass to the baffles *c* substantially without detention, and also without interference with the distribution of the condensate due to the arrangement of the tubes *d*. A cover over the trough 21 would prevent any condensate falling directly into it; if such protection should be desired. The vapors in passing 30 through the grating composed of the open slats or shutters are thereby commingled with the descending condensate; as they are also in passing over and between the baffles *c*.

While the new or improved tower can 40 be used in various distillations, and possibly in other relations, it is more particularly designed for use in distilling the heavy end of crude petroleum. When crude petroleum is distilled under atmospheric pressure without introduction of aeriform fluid into the liquid oil and with gradual elevation of the temperature of said oil, a certain (natural) fraction of the oil distils over before a temperature is attained at which 45 composition commences on a considerable scale. A further (intermediate) fraction then distils over before the distillation of the lubricant (or, if the crude petroleum yields paraffin wax, the lubricant and wax yielding fraction) begins. The precise 50 limits of these fractions are not important here. Toward the close of the distillation of the lubricant (or lubricant and wax yielding) fraction the vapors contain gradually increasing quantities of gummy or asphaltic matters; until finally they are predominantly (if not wholly) composed of such matters, the contents of the still at 55 this time having been reduced nearly to the condition of coke. In effecting such a com-

plete distillation with the apparatus shown, crude petroleum can be supplied to still *m* through pipe *n* until a charge corresponding with the capacity of the still has been introduced. Distillation would then best be 70 carried on with the valves *q* and 16 open and the valves 4, 6, 8, 17 and 23 closed and the interceptor 20 in position to allow liquid to descend from pipes *d* to the lower part of the tower, until after the intermediate 75 fraction has been distilled; say until the condensate leaving the chamber *a* by pipe *z* has a viscosity as high as 65 seconds at 100° F. by Saybolt's Universal Viscosimeter or exhibits a cloud at a temperature as high as 50° F. (whichever characteristic first appears); which point may be taken as about the beginning of distillation of the lubricant (or lubricant and wax yielding) fraction of the crude petroleum. To ascertain this point a specimen of the condensate can be drawn off through the pipe 2. During this part of the run all the condensate from the tower *ad* returns to the still *m* through the pipe *p*. The valve 4 can now be opened 80 and the valve *q* closed; so that all the condensate from the tower *ad* is drawn off as distillate through the pipe 2. Distillation is then further carried on until the condensate from pipe 2 begins (or until just 85 before it begins) to have an objectionable content of gummy or asphaltic matters and would, therefore, be difficult to press for paraffin wax (if from a wax yielding petroleum) or to be given the sulfuric acid and 90 alkali treatment (if from a petroleum with an asphaltic base). At this time the interceptor 20 would best be changed into the position shown in Figs. 3, 4 and 5, in which it conducts condensate from the tubes *d* to 95 the pipe 22 by way of the gutter 31. At the same time (or just previously) the valves 23 and *q* should be opened and the valve 4 closed. Condensate separated from the vapors below the interceptor, which should contain the gummy or asphaltic matters, would be returned to the still *m* through the pipe *p*. Distillation in this way may 100 well be continued as long as the condensate from tubes *d*, collected through draw off 2, 105 is satisfactory. When it becomes unsatisfactory, the interceptor 20 may well be changed into position to allow the condensate from tubes *d* to pass into the lower part of the tower, and either the valve 4 or 110 the valve 8 be opened, the valves 23 and *q* being closed. The valve 8 would be opened and the pipe 4 closed whenever the condensate is too pasty to flow at the temperature of the pipe 2. Distillation may then 115 be continued until the contents of the still are nearly or quite in the condition of dry coke.

During the entire run condensate formed in condenser 11 can be drawn off as distillate 120

through the pipe 15; or if it should be unsatisfactory at any time it can be run back to the still *m* through the pipes 18 and *p*, valve 16 being closed and valve 17 opened. 5 The condensate produced in pipe 13 can be drawn off as distillate at the tail end of said pipe at all times during the run. The still *m* is then steamed out, and when cool is cleaned preparatory to a new run.

10 While it has been mentioned that the distillation with the valve *q* open is continued until the condensate from chamber *a* has a specified viscosity or exhibits a cloud at a specified temperature, it will be understood 15 that such distillation can be continued longer or be arrested sooner, if so desired, and that other details can be varied in carrying out the described mode of using the apparatus shown. This mode is, of course, 20 not necessarily the only one in which the apparatus can be employed. The pipe 5, with valve 6, would be used in case it should be desired to draw off condensate simultaneously from the tubes *d* by way of 25 the interceptor 20 and pipe 22 and from the chamber *a* otherwise than through the pipe 7.

As shown the vapors pass first through the lower and then through the upper part 30 of the tower; but it does not follow that the interceptor of the present invention would only be useful in a tower in which the vapors so pass.

An interceptor formed by slats or shutters 35 20 in connection with gutter 21 and valved pipe 22 would serve, with said slats or shutters stationary in the position shown, for withdrawing the descending condensate or for allowing it to pass on to the lower 40 part of the tower, according as the valve 23 should be open or closed. The condensate falling on such interceptor would fill and overflow the gutter 21; when the valve 23 should be closed. Such an interceptor 45 would have an advantage over the intercepting chamber heretofore employed, in that the gutter would be of small capacity as compared with such prior chamber, and also on account of the greater area of the 50 inclined partitions composed of said slats or shutters over the bottom of such prior chamber. These advantages would result even if the partitions for directing the condensate to the gutter 21 were not formed of 55 slats or shutters; and each of the advantages mentioned could be secured without the other of them. It is evident further that the slats or shutters shown could be opened to a certain extent without ceasing to conduct descending condensate to the gutter 21 60 and that in this position they would form a grating for commingling the vapors and condensate.

I claim as my invention or discovery:

65 1. A tower having (1) a vapor inlet be-

low, (2) a liquid outlet below, (3) a vapor outlet above, (4) a liquid outlet intermediate said vapor inlet and the first mentioned liquid outlet on the one hand and said vapor outlet on the other, (5) a movable interceptor which in one position conveys descending liquid to said intermediate outlet and in another position leaves the interior of the tower approximately clear for liquid to drop past said interceptor and in both positions allows vapors to move upward past said interceptor, (6) reflux fractional condensing means intermediate said interceptor and said vapor outlet, and (7) means for bringing liquid and vapors into contact with each other intermediate said vapor inlet and first mentioned liquid outlet on the one hand and said interceptor on the other, substantially as described. 70

2. A tower having (1) a vapor inlet below, (2) a liquid outlet below, (3) a vapor outlet above, (4) a liquid outlet intermediate said vapor inlet and the first mentioned liquid outlet on the one hand and said vapor outlet on the other, (5) a tilting interceptor which in one position conveys descending liquid to said intermediate outlet and in another position leaves the interior of the tower approximately clear for liquid to drop past said interceptor and in both positions allows vapors to move upward past said interceptor, (6) reflux fractional condensing means intermediate said interceptor and said vapor outlet, and (7) means for bringing liquid and vapors into contact with each other intermediate said vapor inlet and first mentioned liquid outlet on the one hand and said interceptor on the other, substantially as described. 85

3. A tower having (1) a vapor inlet below, (2) a liquid outlet below, (3) a vapor outlet above, (4) a liquid outlet intermediate said vapor inlet and the first mentioned liquid outlet on the one hand and said vapor outlet on the other, (5) a movable interceptor which in one position conveys descending liquid to said intermediate outlet and in another position leaves the interior of the tower approximately clear for liquid to drop past said interceptor and in both positions allows vapors to move upward past said interceptor, (6) reflux fractional condensing means intermediate said interceptor and said vapor outlet, and (7) means for bringing liquid and vapors into contact with each other intermediate said vapor inlet and first mentioned liquid outlet on the one hand and said interceptor on the other, substantially as described. 90

4. A tower having (1) a vapor inlet below, (2) a liquid outlet below, (3) a vapor outlet above, (4) a liquid outlet intermediate said vapor inlet and the first men-

- tioned liquid outlet on the one hand and said vapor outlet on the other, (5) a movable interceptor constituted by a system of tilting slats or shutters and arranged in one position to convey descending liquid to said intermediate outlet and in another position to allow the liquid to descend between said slats or shutters and in both positions to allow vapors to move upward past said interceptor, (6) reflux condensing means intermediate said interceptor and said vapor outlet, and (7) means for bringing liquid and vapors into contact with each other intermediate said vapor inlet and first mentioned liquid outlet on the one hand and said interceptor on the other, substantially as described.
5. A distilling apparatus, comprising heating means, and a tower arranged for the treatment therein of vapors formed by said means and having (1) a vapor inlet below, (2) a liquid outlet below, (3) a vapor outlet above, (4) a liquid outlet intermediate said vapor inlet and the first mentioned liquid outlet on the one hand and said vapor outlet on the other, (5) a movable interceptor which in one position conveys descending liquid to said intermediate outlet and in another position leaves the interior of the tower approximately clear for liquid to drop past said interceptor and in both positions allows vapors to move upward past said interceptor, (6) reflux fractional condensing means intermediate said interceptor and said vapor outlet, and (7) means for bringing liquid and vapors into contact with each other intermediate said vapor inlet and first mentioned liquid outlet on the one hand and said interceptor on the other, substantially as described.
6. The combination with the body of a tower, of frames supported in said tower, slats or shutters journaled in said frames, and means for conducting away liquid intercepted by said slats or shutters, substantially as described.
7. A tower having (1) a vapor inlet below, (2) a liquid outlet below, (3) a vapor outlet above, (4) a liquid outlet intermediate said vapor inlet and the first mentioned liquid outlet on the one hand and said vapor outlet on the other, (5) inclined partitions for intercepting descending liquid intermediate the second mentioned liquid outlet and said vapor outlet, (6) a gutter connected with the second mentioned liquid outlet and provided with an overflow and arranged to receive liquid intercepted by said partitions, (7) reflux condensing means intermediate said inclined partitions and said vapor outlet, and (8) means for bringing liquid and vapors into contact with each other intermediate said vapor inlet and first mentioned liquid outlet on the one hand and said gutter on the other, substantially as described.
8. A tower having (1) a vapor inlet below, (2) a liquid outlet below, (3) a vapor outlet above, (4) a liquid outlet intermediate said vapor inlet and the first mentioned liquid outlet on the one hand and said vapor outlet on the other, (5) inclined partitions for intercepting descending liquid arranged for condensate forming on their under surfaces to drop off without uniting with the intercepted liquid and located intermediate the second mentioned liquid outlet and said vapor outlet, (6) a gutter connected with the second mentioned liquid outlet and provided with an overflow and arranged to receive liquid intercepted by said partitions while allowing condensate from the under surfaces of said partitions to drop past said gutter, (7) reflux condensing means intermediate said inclined partitions and said vapor outlet, and (8) means for bringing liquid and vapors into contact with each other intermediate said vapor inlet and first mentioned liquid outlet on the one hand and said gutter on the other, substantially as described.
9. A distilling apparatus, comprising heating means, and a tower arranged for treatment therein of vapors formed by said heating means and having (1) a vapor inlet below, (2) a liquid outlet below, (3) a vapor outlet above, (4) a liquid outlet intermediate said vapor inlet and the first mentioned liquid outlet on the one hand and said vapor outlet on the other, (5) inclined partitions for intercepting descending liquid intermediate the second mentioned liquid outlet and said vapor outlet, (6) a gutter connected with the second mentioned liquid outlet and provided with an overflow and arranged to receive liquid intercepted by said partitions, (7) reflux condensing means intermediate said inclined partitions and said vapor outlet, and (8) means for bringing liquid and vapors into contact with each other intermediate said vapor inlet and first mentioned liquid outlet on the one hand and said gutter on the other, substantially as described.

In testimony whereof I affix my signature in presence of two witnesses.
